UNITED STATES PATENT OFFICE.

TILLY HAYNES, OF BOSTON, MASSACHUSETTS.

DESIGN FOR A LAVATORY-BASIN.

SPECIFICATION forming part of Design No. 14,023, dated July 3, 1883.

Application filed April 26, 1883. Term of patent 14 years.

To all whom it may concern:

Be it known that I, TILLY HAYNES, a citizen of the United States, residing at Boston, in the county of Suffolk and State of Massachusetts, have invented and produced a new and original Design for a Lavatory-Basin, of which the following is a specification, reference being had to the accompanying drawings, forming part thereof.

Figure 1 is a plan view of my newly-designed lavatory-basin, and Fig. 2 is a longitudinal section thereof, these two views being deemed necessary to fully illustrate my design.

Heretofore lavatory-basins have been made which presented in plan view a circular form, with little or no projecting border-line beyond the body of the basin at its edge.

The leading feature of my design consists in making the border of the basin *a* of an oval form when shown in plan view, as in Fig. 2, the body of the basin, from its lowest point, being made in the form shown in longitudinal section in Fig. 2—that is to say, ovaliform.

D is a wide border extending from the said oval border-line of the basin *a*, and terminating at its borders in a quadrilateral form.

I claim—

1. The design for a lavatory-basin herein shown and described, the same consisting of a basin, *a*, having an oval-shaped border, and a wide border, D, surrounding said oval-shaped border, and an ovaliformed body.

2. The design for a lavatory-basin herein shown and described, the same consisting of a basin, *a*, having an oval-shaped border, an ovaliformed body, and a wide border, D, extending from said oval-shaped border and terminating in a quadrilateral form at its surrounding edge.

TILLY HAYNES.
